FILM REWINDER

Iwan Serrurier, Los Angeles, Calif.

Application April 20, 1936, Serial No. 75,482

6 Claims. (Cl. 242—55)

This invention relates to motion picture film rewinders for use in editing film, measuring film, etc., and has particularly to do with multiple rewinders for simultaneously rewinding two separate films on two separate reels. Multiple rewinders are particularly useful in connection with the synchronizing of sound films with their associated picture films. In such work it is often necessary to drive the two reels of a double rewinder by different amounts to compensate for variations in the lengths of the films supplied thereto.

A broad object of the invention is to provide a double-reel rewinder that is simple in construction, positive and reliable in operation and readily adaptable to single reel operation.

A more specific object is to provide a double-reel rewinder in which the two reels are driven through a differential member so that equal torque is applied to each reel, with fittings for adapting the mechanism for use with a single reel and maintaining positive drive to that reel. This is quite an essential feature as it is well known that in a conventional differential mechanism if no load is placed on one of the differentially driven members that member will rotate and prevent the application of driving torque to the other member.

Various other specific objects and features of the invention will become apparent from the detailed description which refers to the drawing. It is to be understood, however, that while a specific embodiment of the invention is described for purposes of illustration, various departures can be made from the specific structure shown while still employing the essential features of the invention and the invention is therefore to be limited only to the extent set forth in the claims.

In the drawing:

Fig. 1 is a vertical sectional view through a rewinder in accordance with the invention;

Fig. 2 is a detailed sectional view illustrating one method of adapting the machine for use with a single reel;

Fig. 3 is a detailed sectional view illustrating a second method of adapting the machine for use with a single reel; and

Figs. 4, 5 and 6 are perspective views of various fittings employed for adapting the machine for the various modes of operation illustrated in Figs. 1, 2 and 3.

Referring to Fig. 1, my machine comprises a main casing 1 which also serves as a supporting framework for the rest of the mechanism. This frame 1 is provided with a base 2 and is adapted to be screwed or otherwise secured to a work

bench or table. The frame 1 comprises in addition a pair of parallel oppositely disposed end walls 3 and 4, respectively, which have formed integrally therewith journals 5, 6, 7 and 8 for supporting various rotating elements of the machine.

Thus the journal 8 rotatably supports a sleeve 9 which extends completely through the journal 8 and projects therebeyond both interior and exterior of the casing. On that portion projecting within the casing is mounted a spur gear 10 which is keyed to the sleeve. The gear 10 rides against the inner end of the journal 8. To maintain the sleeve 9 and gear 10 against longitudinal motion with respect to the journal 8, a bushing 11 is secured as by a set screw 12 to that end portion of the sleeve 9 projecting outwardly of the casing. It will be observed, therefore, that the sleeve 9 having the gear 10 anchored thereto is free to rotate within the journal 8 but is prevented from moving longitudinally with respect thereto.

Journalized within the sleeve 9 is a reel shaft 14, this shaft extending through and beyond the sleeve 9 at both ends and being rotatably supported at its right end in the journal 7 of the casing 1. Shaft 14 has pinned thereto a spur gear 15 and the shaft is held against longitudinal movement by a bushing 16 and a bushing 17. Bushing 16 encircles the shaft and abuts against the gear 15 on one end and against the sleeve 9 on the other end. The bushing 17 likewise encircles the shaft and is positioned between the gear 15 and the inner end of the journal 7.

As shown in Fig. 1, the spur gears 10 and 15 are not engaged with any other gears and are free to rotate. Therefore, both the sleeve 9 and the shaft 14 are perfectly free to rotate in the condition shown. However, a differential mechanism employing a pair of spur gears 20 and 21 adapted to be meshed with the gears 10 and 15, respectively, is mounted within the case 1 below the shaft 14 for applying torque independently to shaft 14 and the sleeve 9.

The gears 20 and 21 are supported for free rotation upon a drive shaft 22 which is rotatably supported in the journals 5 and 6 in the end walls 3 and 4 of the housing. A crank handle 23 is provided on the right end of shaft 22 exterior of the casing 1 for rotating the latter. Gear 20 has attached thereto a bevel gear 24 and gear 21 has attached thereto a bevel gear 25. These bevel gears 24 and 25 mesh with differential bevel gears 26 which are freely rotatably mounted on stub shafts 27 extending radially with respect to the

shaft 22 and projecting from a frame member 28 which is pinned to shaft 22. The assembly comprising gears 20 and 24 is maintained in proper spaced relation with respect to the gears 28 by a bushing 29 surrounding the shaft 22 between the bevel gear 24 and the frame member 28 and a thrust block 30 secured to shaft 22 and bearing against the outer end of gear 20. The assembly comprising the bevel gear 25 and the spur gear 21 are similarly maintained in proper longitudinal position by a bushing 31 and a thrust member 32.

When the shaft 22 is in the position shown, the spur gears 20 and 21 are out of mesh with the gears 10 and 15. However, by forcing the shaft 22 to the left the gear 20 meshes with the gear 10 and the gear 21 meshes with the gear 15, thereby operatively connecting the gear 20 to the sleeve 8 and the gear 21 to the shaft 14. Thereafter, rotation of shaft 22 by the crank 23 applies equal torques to the bevel gears 24 and 25 through the differential gears 26, which torques are transmitted through the gears 20 and 21, respectively, to sleeve 8 and shaft 14, respectively. If the resistance to motion of either one of the elements 8 or 14 is greater than that of the other, then the differential gears 26 will rotate on the stub shafts 27 to cause the free member to rotate faster than the impeded member.

The mechanism described actuates two film reels 35 and 36, respectively, which are mounted upon that portion of the shaft 14 extending to the left of the casing 1. Each reel 35 and 36 is of standard construction and comprises a pair of end plates 37 extending outwardly from a cylindrical hub 38 upon which the films are wound. Each spool is also provided with an inner hub or spindle 39 which is dimensioned to fit about the shaft 14 and is provided with a groove or keyway 40 for receiving an element on the shaft 14 or bushing 11 for restraining free rotation of the reel. Thus the bushing 11 is provided with a finger 41 extending parallel to and adjacent the surface of the shaft 14 for projecting into the groove 40 of reel 36 and thereby forcing the reel 36 to rotate with the sleeve 8. The shaft 14, on the other hand, is provided with a wire key 43 which projects from the surface of the shaft 14 into the groove 40 of reel 35 to force the latter to rotate with the shaft 14.

The outer end portion 45 of the shaft 14 may be pivotally secured to the remainder of the shaft as by pin 46 to permit the portion 45 to be turned at right angles to the remainder of the shaft, as shown in dotted lines, to maintain the reels 35 and 36 in place upon the shaft. A bushing 47 may be positioned between reels 35 and 36 to maintain them in proper spaced relation with respect to each other. This bushing 47 is provided with a groove 48 therein to permit the bushing to move into place past the key 43. The bushing 47 is shown in perspective in Fig. 6.

With the machine as set up in Fig. 1, either reel 35 or 36 may be spun in either direction independent of the other by virtue of the fact that neither of the gears 10 or 15 is meshed with the driving mechanism. On the other hand, by merely pushing the handle 23 in toward the case 1 of the machine and rotating the handle, equal driving torque may be applied to both reels to maintain the films being rewound in taut condition.

Occasionally it may be desired to employ the machine shown in Fig. 1 with only one reel for rewinding a single film. The apparatus as set

up in Fig. 1 would be unsuitable for this purpose since rotation of the handle 23 would rotate only one reel, that is, the one not in use, and the reel having film thereon would remain stationary. In other words, in order to positively rotate either reel the sleeve 8 and the shaft 14 must be locked together to rotate in unison. There are two ways of mounting a single reel on the shaft 14 and two methods of simultaneously interlocking the shaft 14 and the sleeve 8. These two methods are shown in Figs. 2 and 3, respectively.

In Fig. 2 the outer reel 35 alone is employed and is locked to the shaft 14 in the same manner as is the reel 35 in Fig. 1, that is, the key 43 of the shaft engages the groove 48 of the reel. To perform the dual functions of locking the sleeve 8 to the shaft 14 and of spacing the reel 35 from the bushing 11, a bushing 50 is employed. This bushing is provided with a groove 51 which extends from one end to the other and slips over the tongue 41 on the bushing 11 at one end and slips over the key 43 on the shaft 14 at the other end, thereby preventing relative rotation between the bushing 11 and the shaft 14.

In the arrangement shown in Fig. 3 the single reel employed is positioned adjacent the case, the reel 35 occupying exactly the same position as shown in Fig. 1. However, in this case the reel 35 is eliminated and to space the reel 36 from the outer end of the shaft 14 and to interlock the bushing 11 and the shaft against relative rotation, an auxiliary bushing 53 is employed. This bushing has a groove or keyway 54 extending therethrough, which groove is engaged by the key 43 on shaft 14 to prevent relative rotation of the bushing with respect to the shaft. To prevent relative rotation between the bushing 53 and the bushing 11, bushing 53 is provided with a tongue 55 extending from one end thereof, which tongue is extended into the groove 48 of the reel 36. Since the reel is restrained against rotation with respect to the bushing 11 by the tongue 41 on the latter and is also restrained from rotation with respect to the bushing 53 by the tongue 55 on that member, there can be no relative rotation between the bushings 53 and 11. For convenience the bushing 53 is shown made in two pieces, one piece 57 corresponding in general dimensions and shape to the bushing 50 except that it is of reduced size at one end and the other piece constituting a collar 58 adapted to fit over the reduced end of piece 57 and be secured in place by a set screw 59. Collar 58 is identical with bushing 11.

As previously indicated, the invention has been described with reference to a particular construction which has been found to be satisfactory but many and various modifications can be made in the particular structure shown and the invention is therefore to be limited only as set forth in the appended claims.

I claim:

1. A film rewinder of the type described, comprising a casing member including a wall having a journal therein, a hollow sleeve member rotatably supported in said journal and projecting therefrom into said casing member, a shaft member journaled in said sleeve member for rotation with respect thereto and projecting a substantial distance therebeyond interior and exterior of said casing, driving means coupled to said sleeve and shaft within said casing for applying torque to each irrespective of the relative speeds of said sleeve and shaft, a pair of film reels having axial apertures dimensioned to fit

- on said shaft and having grooves in the walls of said apertures, said reels being mounted on said shaft one adjacent said casing and the other adjacent the outer end of the shaft, a tongue 5 on said sleeve member extending outwardly adjacent the surface of said shaft into the said groove in the adjacent reel to force the latter to rotate with the sleeve, and a key member on said shaft extending radially from the shaft into 10 the said groove in the outer reel to cause the latter to rotate with said shaft.
2. A film rewinder of the type described, comprising a casing member having spaced apart walls and juxtaposed journals therein, a hollow 15 sleeve member rotatably supported in one of said journals and projecting therefrom into said casing member, a shaft member journaled in said sleeve member for rotation with respect thereto, said shaft member extending through said casing and being journaled in said juxtaposed journal in the other wall, said shaft also projecting a substantial distance beyond said sleeve exterior of said casing, driving means coupled to said sleeve and shaft within said casing for applying 20 torque to said sleeve and shaft irrespective of their relative speeds of rotation, a pair of film reels having axial apertures dimensioned to fit on said shaft and having grooves in the walls of said apertures, said reels being mounted on said shaft one adjacent said casing and the other adjacent the outer end of said shaft, a tongue 25 on said sleeve member extending outwardly adjacent the surface of said shaft into said groove in the adjacent reel to cause the latter to rotate with the sleeve, and a key member on said shaft extending radially from the shaft into the said groove in the outer reel to cause the latter to rotate with said shaft.
3. A film rewinder as described in claim 2 30 including a drive shaft parallel to said one shaft with a frame fixed to said drive shaft, said frame having bevel gears mounted thereon for free rotation about axes extending radially from said drive shaft, a pair of spur gears freely rotatably 35 mounted on said drive shaft on opposite sides of said frame, a bevel gear on the inner side of each of said first mentioned spur gears, thrust bearing members on said drive shaft for maintaining said spur gear members in predetermined spaced 40 apart relation with respect to each other and said frame member, and spur gears on said sleeve and said first mentioned shaft member, respectively, adapted to mesh with said two spur 45 gears on said drive shaft.
4. A film rewinder as described in claim 2 50 including a drive shaft parallel to said one shaft with a frame fixed to said drive shaft, said frame having bevel gears mounted thereon for free rotation about axes extending radially from said drive shaft, a pair of spur gears freely rotatably 55 mounted on said drive shaft on opposite sides of said frame, a bevel gear on the inner side of each of said first mentioned spur gears, thrust bearing members on said drive shaft for maintaining 60 said spur gear members in predetermined spaced 65 said spur gear members in predetermined spaced
- apart relation with respect to each other and said frame member, and spur gears on said sleeve and said first mentioned shaft member, respectively, adapted to mesh with said two spur gears on said drive shaft, said drive shaft being longitudinally slidably mounted on its journals in said casing for movement to carry said spur gears thereon into and out of mesh with the associated spur gears on said sleeve members and said first mentioned shaft, respectively. 5
5. A film rewinding machine of the type described comprising a casing, a sleeve journaled in a wall of said casing and projecting there-through, a shaft journaled in said sleeve and projecting therebeyond a substantial distance, a reel 10 having an aperture therein dimensioned to fit snugly over said shaft, the axial length of said reel being less than half the length of the projecting portion of said shaft, means on the outer end of said shaft for preventing escape of a reel 15 positioned thereon, means within said casing for simultaneously applying torque independently to said sleeve and said shaft, a tongue on said sleeve extending outwardly therefrom parallel to and closely adjacent the surface of said shaft, a key 20 projecting from said shaft over a distance along said shaft, said reel having a groove therein for engaging said key and preventing relative rotation between the reel and shaft, and a bushing 25 adapted to be mounted on said shaft between 30 said sleeve and said reel for spacing the reel from said sleeve, said bushing having a groove therein dimensioned to receive said tongue and to receive said key on said shaft, the latter being so positioned longitudinally on said shaft as to be 35 engaged over part of its length by the groove in said bushing and over another part of its length by the groove in said reel. 40
6. A film rewinding machine comprising a casing having a wall with a journal therein, a hollow sleeve rotatably supported in said journal and extending from the interior to the exterior of said casing, a shaft rotatably supported within said sleeve and extending therebeyond both within and without the casing, differential means within 45 said casing for simultaneously applying equal torque to said shaft and said sleeve, said sleeve having a tongue extending therefrom exterior of the casing parallel to and alongside the surface of said shaft, a film reel apertured to fit on said shaft and of axial length less than half the length of the protruding portion of said shaft, a groove in said reel for receiving said tongue and locking the reel against rotation with respect to said sleeve, a key on said shaft positioned adjacent 55 the outer end thereof, stop means on the outer end of said shaft, and a bushing for spacing said reel from the outer end of said shaft and preventing relative rotation between said sleeve and shaft, said bushing being apertured to fit over 60 said shaft and having a groove therein for receiving the key on said shaft and said bushing also having a tongue on its inner end adapted to fit into and interlock with the groove in said reel. 65

Hereby enters this disclaimer to claims 1 and 2 in said specification.

[Official Gazette June 28, 1938.]

- on said shaft and having grooves in the walls of said apertures, said reels being mounted on said shaft one adjacent said casing and the other adjacent the outer end of the shaft, a tongue 5 on said sleeve member extending outwardly adjacent the surface of said shaft into the said groove in the adjacent reel to force the latter to rotate with the sleeve, and a key member on said shaft extending radially from the shaft into 10 the said groove in the outer reel to cause the latter to rotate with said shaft.
2. A film rewinder of the type described, comprising a casing member having spaced apart walls and juxtaposed journals therein, a hollow 15 sleeve member rotatably supported in one of said journals and projecting therefrom into said casing member, a shaft member journaled in said sleeve member for rotation with respect thereto, said shaft member extending through said casing and being journaled in said juxtaposed journal in the other wall, said shaft also projecting a substantial distance beyond said sleeve exterior of said casing, driving means coupled to said sleeve and shaft within said casing for applying 20 torque to said sleeve and shaft irrespective of their relative speeds of rotation, a pair of film reels having axial apertures dimensioned to fit on said shaft and having grooves in the walls of said apertures, said reels being mounted on said shaft one adjacent said casing and the other adjacent the outer end of said shaft, a tongue 25 on said sleeve member extending outwardly adjacent the surface of said shaft into said groove in the adjacent reel to cause the latter to rotate with the sleeve, and a key member on said shaft extending radially from the shaft into the said groove in the outer reel to cause the latter to rotate with said shaft.
3. A film rewinder as described in claim 2 30 including a drive shaft parallel to said one shaft with a frame fixed to said drive shaft, said frame having bevel gears mounted thereon for free rotation about axes extending radially from said drive shaft, a pair of spur gears freely rotatably 35 mounted on said drive shaft on opposite sides of said frame, a bevel gear on the inner side of each of said first mentioned spur gears, thrust bearing members on said drive shaft for maintaining said spur gear members in predetermined spaced apart relation with respect to each other and said frame member, and spur gears on said sleeve and said first mentioned shaft member, respectively, adapted to mesh with said two spur 40 gears on said drive shaft.
4. A film rewinder as described in claim 2 45 including a drive shaft parallel to said one shaft with a frame fixed to said drive shaft, said frame having bevel gears mounted thereon for free rotation about axes extending radially from said drive shaft, a pair of spur gears freely rotatably 50 mounted on said drive shaft on opposite sides of said frame, a bevel gear on the inner side of each of said first mentioned spur gears, thrust bearing members on said drive shaft for maintaining said spur gear members in predetermined spaced 55 apart relation with respect to each other and said frame member, and spur gears on said sleeve and said first mentioned shaft member, respectively, adapted to mesh with said two spur gears on said drive shaft.
5. A film rewinding machine of the type described comprising a casing, a sleeve journaled in a wall of said casing and projecting there-through, a shaft journaled in said sleeve and projecting therebeyond a substantial distance, a reel 60 having an aperture therein dimensioned to fit snugly over said shaft, the axial length of said reel being less than half the length of the projecting portion of said shaft, means on the outer end of said shaft for preventing escape of a reel 65 positioned thereon, means within said casing for simultaneously applying torque independently to said sleeve and said shaft, a tongue on said sleeve extending outwardly therefrom parallel to and closely adjacent the surface of said shaft, a key 70 projecting from said shaft over a distance along said shaft, said reel having a groove therein for engaging said key and preventing relative rotation between the reel and shaft, and a bushing adapted to be mounted on said shaft between 75 said sleeve and said reel for spacing the reel from said sleeve, said bushing having a groove therein dimensioned to receive said tongue and to receive said key on said shaft, the latter being so positioned longitudinally on said shaft as to be 80 engaged over part of its length by the groove in said bushing and over another part of its length by the groove in said reel.
6. A film rewinding machine comprising a casing having a wall with a journal therein, a hollow 85 sleeve rotatably supported in said journal and extending from the interior to the exterior of said casing, a shaft rotatably supported within said sleeve and extending therebeyond both within and without the casing, differential means within 90 said casing for simultaneously applying equal torque to said shaft and said sleeve, said sleeve having a tongue extending therefrom exterior of the casing parallel to and alongside the surface of said shaft, a film reel apertured to fit on said shaft and of axial length less than half the length of the protruding portion of said shaft, a groove in said reel for receiving said tongue and locking the reel against rotation with respect to said sleeve, a key on said shaft positioned adjacent 95 the outer end thereof, stop means on the outer end of said shaft, and a bushing for spacing said reel from the outer end of said shaft and preventing relative rotation between said sleeve and shaft, said bushing being apertured to fit over 100 said shaft and having a groove therein for receiving the key on said shaft and said bushing also having a tongue on its inner end adapted to fit into and interlock with the groove in said reel.
